UNITED STATES PATENT OFFICE

138,972

DESIGN FOR A TURRET INJECTION
MACHINE

Walter Ernst, Mount Gilead, Ohio, and Reider Thoreson, Detroit, Mich., assignors to H-P-M. Development Corporation, Wilmington, Del., a corporation of Delaware

Application March 2, 1944, Serial No. 112,769

Term of patent 14 years

(Cl. D55—1)

To all whom it may concern:

Be it known that we, Walter Ernst and Reider Thoreson, citizens of the United States, residing respectively at Mount Gilead and Detroit, in the counties of Morrow and Wayne and States of Ohio and Michigan, have invented a new, original, and ornamental Design for a Turret Injection Machine, of which the following is a specification, reference being had to the accompanying drawings, forming a part thereof, wherein:

Figure 1 is a side elevational view of a turret injection machine, showing our new design.

Figure 2 is a side elevational view of the injection machine as viewed from the opposite side thereof from that illustrated in Figure 1.

Figure 3 is a top plan view of the injection machine.

Figure 4 is an end elevational view of the injection machine as viewed from the left-hand end thereof with reference to Figure 1.

Figure 5 is an end elevational view of the machine as viewed from the right-hand end thereof with reference to Figure 1.

We claim:

The ornamental design for a turret injection machine, substantially as shown.

WALTER ERNST.
REIDER THORESON.
